UNITED STATES PATENT OFFICE.

HARRY C. GAMMETER, OF CLEVELAND, OHIO, ASSIGNOR TO THE AMERICAN MULTIGRAPH COMPANY, OF CLEVELAND, OHIO, A CORPORATION OF OHIO.

APPARATUS FOR MAKING LINE-SLUGS.

1,122,726.

Specification of Letters Patent. Patented Dec. 29, 1914.

Application filed November 15, 1913. Serial No. 801,170.

To all whom it may concern:

Be it known that I, HARRY C. GAMMETER, a citizen of the United States, residing at Cleveland, in the county of Cuyahoga and State of Ohio, have invented a certain new and useful Improvement in Apparatus for Making Line-Slugs, of which the following is a full, clear, and exact description, reference being had to the accompanying drawings.

My prior application No. 783,722, filed August 8th, 1913 describes and claims a process of making short height-to-paper line slugs having holding devices on their opposite sides, such process, briefly stated, consisting of the steps of casting a slug in a T-form with ribs on its sides, and thereafter breaking down the upper portion of the ribs and removing the lower portion of the slug to make a short slug with lugs on its sides separated from its head.

The object of the present invention is to provide an efficient mechanism for casting the blank from which such finished slug is made by removing the lower portion and breaking down the side ribs.

The present invention relates to a peculiar mold for casting such slug and a peculiar ejector for removing the original slug from the mold, both these parts being adapted for mounting in the standard Mergenthaler machine.

The invention is hereinafter more fully explained and its essential characteristics set out in the claims.

In the drawings, Figure 1 is a cross section of a Mergenthaler mold wheel, ejector and trimming knives; Fig. 2 is a cross section of such wheel through the melting pot and matrices; Fig. 3 is a face view of a portion of the mold wheel; Fig. 4 is a cross section on the line 4—4 of Fig. 3 looking downwardly; Fig. 5 is a cross section on the line 5—5 of Fig. 1; Fig. 6 is a perspective view of the slug cast by this mechanism.

In the drawing, 10 designates the usual disk-like mold wheel of the Mergenthaler machine, having a hub 11 mounted on a rotatable stud 12, which is in turn mounted in a suitable bearing 14. Rigid with this bearing 14 is an arm 16 carrying a guideway 17 parallel with the axis of the wheel. Slidably mounted on this guideway 17 is an ejector slide 18, which, as shown, has a pin 19 in engagement with the slot of a face

cam 20; mounted on a rotatable shaft 21 and adapted to reciprocate the slide.

The wheel 10 has on its outer periphery suitable gear teeth 22, and carries a mold block 24 having the usual face for the matrices, and having an inwardly projecting portion 26 fitted into an opening in the wheel. This mold block 24 in my invention is provided with a peculiarly formed slot or mold space, indicated at 27, which is adapted to form the line slug of the desired shape, as hereinafter more fully described.

At the right or the front of the mold wheel is a frame (not shown) rigidly carrying a trimmer knife 28 and also carrying a trimmer knife 29, which is adjustably mounted thereon. The trimmer knife 28 remains always at a fixed distance from the center of the mold wheel, while the knife 28 may be moved toward or away from the center of the wheel to allow for different thicknesses of slugs.

The slug which I desire to cast is shown particularly in Fig. 6. It has a narrow body portion 30, a T-shaped head 31 overhanging the body portion and having on its upper edge characters indicated at 32, while beneath the overhanging portions of the head 31 are narrow vertical ribs 33 placed at intervals along each side of the slug, extending downwardly from the under side of the head. In the specific slug shown, the ribs at their upper ends where they join the head project a distance less than that of the head, (say about half the head projection), and from the head downward the ribs incline inwardly till their lower ends preferably merge with the side of the shank about half way down it.

To form the slug described, the mold block 24 is provided with a narrow cavity 30^a and lateral cavities 31^a at the front or edge thereof, and leading from the lateral cavities 31^a to points intermediate of the narrow cavity 30^a are grooves 32^a on each side, these grooves having their outer faces inclined from points on the corresponding head cavity to points on the shank cavity. In other words, the mold space is complementary to the slug shape shown in Fig. 6.

The slide 18 fitted against the face 35 of the guideway 17 is suitably dove-tailed into the guideway, as at 36, in Fig. 5. Pins 38, 110

carried on forwardly projecting portions of the head, engage an ejector blade which is guided by the face 35 of the guideway. In the regular Mergenthaler machine, the mold 5 24 has a rectangular cavity forming the body of the slug, so spaced from the center of the mold wheel that its inner side is in alinement with the face 35 of the guideway 17, as indicated by dot-and-dash lines at 39 10 in Fig. 1. The trimming knife 28 is fixed so that its cutting edge is on this line and the trimming knife 29 may be adjusted so that it is adapted for the various thickness of the slugs. The ejector blade in such 15 standard machine is held against the face of the guideway by means of a guide bar 40 bearing against the outer face of the ejector blade and held in contact therewith by suitable springs, as indicated at 41, these 20 springs and guide bar being suitably mounted in a casing 42 carried by the guideway 17.

In order to cast slugs of the character I have shown and described in the ordinary 25 Mergenthaler line casting machine without disturbing the guideway 17 and by means of the usual ejector slide 18, and without disturbing the stationary trimming knife, I provide the special mold adapted to cast 30 this slug with the cavities positioned so that the inner side of the head 31 will be suitably trimmed by the trimmer knife 28 by bringing such inner side to the line 39 in alinement with the face 35 described. The 35 outer trimmer knife 29 is so adjusted as to properly trim the other side of the head 31 of the slug. This brings the shank 30 of the slug a distance away from the face 35, which makes it impossible to employ the 40 usual ejector blade sliding along this face 35. Accordingly, I provide an ejector blade of the following form: The blade 45 is provided at its rear end with a face 46 resting against the face 35 of the guideway 17, and 45 the outer face 47 of the ejector blade is in alinement with the outer side of the shank 30 of the slug. At the rear the blade is provided with suitable holes 48, Figs. 1 and 4, which receive the pins 38 of the head 18. 50 In order to bring the inner side of the blade in alinement with the inner side of the shank of the slug I cut away a portion of the blade, as at 48, for a distance back of the blade at least equal to the distance the 55 shank stands above the fixed line 39. As shown, this cut away portion is formed of such a length that the blade may extend through the mold a distance sufficient to push the slug past the trimmer knives and 60 the frame that holds them. At the forward end of the guideway 17 adjacent the mold, I mount a slide block 50 between the face 35 and the cut away portion 48 of the ejector blade to insure the blades alining with the 65 mold face of the mold. The blade is held

against this block by means of the usual guide bar 40 and the springs 41, as heretofore described.

In operation the mold 24 is brought by the rotation of the wheel 10 to the spout 52 of the melting pot 54, indicated in Fig. 2. The mold space is then filled with the molten metal, the matrices, indicated at 55, forming the characters on the slug in the usual manner. Thereafter the wheel 10 is rotated until the slug comes opposite the ejector blade 45. At this time the shaft 21 is rotated, which, through the cam 20 and the ejector slide 18, shoves the ejector blade forward, pushing the slug forwardly from the mold and at the same time trimming the sides of the heads 31 by means of these trimming knives 28 and 29. The ejector blade 45 is preferably made substantially as wide as the length of the slug, it being held against lateral movement by means of the pins 38 occupying the holes 48.

It should be noted particularly that the guide on which the ejector plate slides is on a standard fixed line in the Mergenthaler machine, and I avail myself of this, notwithstanding the peculiar form of the slug, by making a narrow ejector blade and spacing it from the slide, as described. The ejector blade is thus adapted to act on the narrow shank of the slug and, at the same time, is guided by the standard fixed plane of the support in the machine. Accordingly with my invention it is only necessary to provide the standard Mergenthaler machine with my special mold and with my spaced ejector, as the same ejector guide and operating mechanism and the same trimming knives may be used in their standard positions.

Having thus described my invention, what I claim is:

1. In an apparatus for making line slugs, the combination, with matrices, of a mold having a space for the shank and spaces for the head and spaces for the ribs on the sides of the shank and below the head which incline outwardly toward the head, so that the width of the slug through the ribs some distance below the head is less than the width of the head.

2. The combination of a mold wheel, a mold thereon, a guide at right angles to the wheel, an ejector having a driving portion slideable along the guide and having a reduced blade spaced from the guide, and a block between the reduced blade and guide.

3. The combination of a mold wheel, a mold thereon, a continuous guiding surface at right angles to the wheel, an ejector blade having a driving portion slideable along said guiding surface, said blade having a free portion spaced from the guiding surface, and a distance block between the free portion and the guiding surface.

4. The combination of a mold wheel, a mold thereon having cavities for casting a slug with a shank and a T-head, a stationary guide, an ejector slideable along the 5 guide and having a reduced portion alining with the shank of the mold, and means for guiding the reduced portion of the blade. 45
5. The combination of a mold wheel, a mold thereon, a guiding surface, an ejector 10 having a driving portion slideable along the guiding surface, said ejector having a blade spaced from the guiding surface for a length at least equal to the height of the slug cast by the mold, and means for guiding the 15 ejector blade near its free end.
6. The combination of a mold wheel, a mold thereon having a cavity for the shank of the slug, and lateral cavities for an overhanging head, a guiding surface substantially in line with one edge of the head, an ejector slideable on said guiding surface and having a blade alining with the shank portion of the mold, and a block between the blade and guiding surface substantially 20 equal in thickness to the overhang of the head of the slug. 25
7. The combination of a mold wheel, a mold thereon having a cavity for the body of the slug and lateral cavities for a T-head 30 of the slug, a stationary guide on one side of the mold substantially in the line of one edge of the head, a stationary knife on the other side of the mold substantially in the same line, an ejector slideable on the stationary guide and having a blade parallel therewith and spaced therefrom to engage the shank of the slug in the mold, and a knife to engage the other edge of the head 35 of the slug. 40
8. A means of ejecting a line slug which has a head wider than its shank consisting of a stationary guide substantially alining
- with one side of the head, and a blade whose rear portion slides along said guide and whose forward portion is spaced from said 45 guide and alines with the shank.
9. The combination, with a mold adapted to form a line slug having a shank and a T-head, of a guide set back from the line of the shank, and an ejector slideable along 50 the guide and having its rear portion engaging it and its forward end spaced therefrom into alinement with said shank.
10. The combination, with matrices, of a mold having a casting space defining a parallel sided shank, an overhanging head, and inclined ribs leading from the opposite sides of the shank approximately midway between the head and foot and continuing outwardly to the under side of the head approximately midway between the outer side of the shank and the outer edge of the head. 55 60
11. A mold for casting a line slug comprising a parallel sided cavity for the shank, lateral grooves for the head, and grooves at 65 the sides of the shank cavity extending from that cavity in an outward incline to the under side of the head, such grooves on opposite sides of the shank being at no point as far apart as the outer edges of the head. 70
12. The combination, with a melting pot and matrices, of an interposed mold having a space for a line slug shank, a T-head, and continuous separated inclined ribs extending up the sides of the shank toward 75 the head and terminating at the under side of the head a material distance within the outer edges of the head.

In testimony whereof, I hereunto affix my signature in the presence of two witnesses. 80
